UNITED STATES PATENT OFFICE.

PHILIP W. GENGEMBRE, OF BOSTON, MASSACHUSETTS.

IMPROVEMENT IN BODKINS FOR PASSING ENLARGED SHANKS OF BUTTONS THROUGH CLOTH.

Specification forming part of Letters Patent No. 44,416, dated September 27, 1864.

To all whom it may concern:

Be it known that I, PHILIP W. GENGEMBRE, of Boston, in the county of Suffolk and State of Massachusetts, have made a new and useful invention, having reference to the Application of Button-Fastenings to Cloth or Other Material; and I do hereby declare the same to be fully described in the following specification, and represented in the accompanying drawings, of which—

Figure 1 denotes a side view, Fig. 2 an edge view, and Fig. 3 a longitudinal section, of the needle or director used in my method of applying a button-fastening to a piece of cloth.

My present invention is intended for the speedy accomplishment of the fixation of or application to cloth or other material of the button-fastening on which Letters Patent, numbered 41,292 of United States patents, were granted to me on the 19th day of January, A. D. 1864.

Fig. 4 represents a section of a button and its fastening, of the kind referred to, as combined with a piece of cloth. In the said figure, A denotes the body of the button, whose back plate, b, is connected with the cloth B by the button fastening, which consists not only of a tubular piece of vulcanized india-rubber, D, but a metallic catch, C, the said catch being constructed with a head, d, a shank, e, and a small foot or projection, e. The spring D encompasses the shank e, and is arranged between the button A and the cloth B, or material to which the button-fastening is applied. The shank e enters a slot in the back plate of the button, the said button being subsequently turned around ninety degrees, so as to connect it with the fastening, and as a consequence to the cloth.

For the insertion of the shank of the fastening in the cloth and in the elastic spring or guard D, I employ an implement made substantially as shown in Figs. 1, 2, and 3—that is to say, it consists of a tapering needle or piercer, E, slit lengthwise from its head toward its point, and having an eye, f, carried transversely across or made within it and close to its base or rear end, such needle or piercer being pointed at its front end. The

two parts h h on each side of the slit, should be elastic, so as to be capable of being easily sprung apart from one another, and each may be hollowed or grooved lengthwise on its inner surface, in order to readily admit the shank e and allow the projecting parts of its foot e to enter the eye or eyes f in the two parts h h. The eye or eyes f serve with the foot to so connect the piercer to the shank as to enable the piercer to draw the shank through a piece of cloth and a spring, D, when the piercer may be used for the purpose.

The mode of using this implement may be thus described: The cloth at the place where it is to receive the button-fastening is to be punctured by the piercer, which, after having been forced nearly its entire length through the cloth, is to have the tubular spring D pressed on it over its point and so as to encompass the piercer, the spring also being forced longitudinally on the piercer and close up to the cloth. Next the catch should have its end or part e inserted between the springs of the piercer, and should be pressed against the piercer so as to force such piercer entirely through the cloth and beyond the spring D. As the piercer may pass out of the spring, the latter, by its contractile power, will close on the shank of the catch and hold the catch firmly in place within the cloth.

The form of the eye or eyes, as well as that of the slit of the piercers, may be varied as circumstances may require, in order for it to receive and fit and fasten to the fastening part e of the shank e.

With my said implement and mode of using it the button-fastenings can be applied and fixed to cloth or clothes with greater accuracy and dispatch, or with much advantage, comparatively speaking.

I do not claim a piercer having a single notch or recess in its head.

I claim as my invention—

The implement or piercer made with the springs or clasps h h, and eye or eyes f, or the equivalent thereof, the same being substantially as and for the purpose specified.

Witnesses: P. W. GENGEMBRE.
